US00D976907S

(12) **United States Design Patent** (10) **Patent No.:** **US D976,907 S**
(45) **Date of Patent:** **** Jan. 31, 2023**

(54) **HANDHELD GAME CONSOLE**

(71) Applicant: **SHENZHEN KONKR TECHNOLOGY CO., LTD.**, Shenzhen (CN)

(72) Inventor: **Zheng Song**, Shenzhen (CN)

(73) Assignee: **SHENZHEN KONKR TECHNOLOGY CO., LTD.**, Shenzhen (CN)

(**) Term: **15 Years**

(21) Appl. No.: **29/762,368**

(22) Filed: **Dec. 16, 2020**

(30) **Foreign Application Priority Data**

Nov. 20, 2020 (CN) 202030705697.9

(51) **LOC (14) Cl.** **14-02**

(52) **U.S. Cl.**

USPC **D14/401**
